UNITED STATES PATENT OFFICE

JOHN P. SCHREY, OF PITTSBURGH, PENNSYLVANIA

ELECTRIC TOY FENCE

Application filed December 3, 1928. Serial No. 323,389.

This invention relates to a toy fence, such as used with Christmas trees, the general object of the invention being to provide lamps for some of the posts of the fence, with base pieces for the fence through which the conductors for the lamps pass, with plug and socket means for connecting the conductors of the different base pieces together so that fences of various sizes and shapes can be readily assembled.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a plan view showing one form of fence which may be constructed from a plurality of sections constructed in accordance with this invention.

Figure 2 is a front view of said fence.

Figure 3 is an elevation partly in section of one of the sections of the fence.

Figure 4 is an enlarged sectional view through the lower part of this section.

Figure 5 is a section on line 5—5 of Figure 4.

Figure 6 is a section on line 6—6 of Figure 4.

Figure 7 is a section on line 7—7 of Figure 4.

Figure 8 is a sectional view through the lower part of a section having a post at each end thereof which is provided with a lamp, this view being a section through the gate carrying section.

Figure 9 is a plan view partly in section of a base section having a plug at each end thereof.

Figure 10 is a similar view of a base section having a socket at each end thereof.

Figure 11 is a view of one of the socket members.

As shown in these views, the fence comprises the posts 1, the rails 2, which have tangs 2' at their ends engaging slots 3 in the posts, and

the U-shaped wires 4 which pass through the rails and are vertically arranged, as shown. Thus the fence is composed of sections which are detachably connected together by the tangs, and in carrying out my invention, I 55 arrange lamps 5 on some of the posts and provide a base 6 to which the lower ends of the posts are connected and through which the conductors for the lamps pass. This base is made up of a plurality of sections, each section 60 being formed of a channel-shaped member 7 and two strips of non-conducting material 8 which are placed in the channel-shaped member and these strips are held in place by bending inwardly the lower edges of the flanges, 65 as shown in Figures 6 and 7. A socket member 9 is placed in each end of each section of the base, said socket member being formed with the double socket 10 which is transversely arranged and with the single socket 11 70 which extends at right angles to the socket 10, the socket 10 registering with the holes 12 formed in the sides of the channel-shaped member. Each socket member is preferably 75 formed of a sheet of metal bent upon itself with parts thereof shaped to form the sockets, as clearly shown in Figure 11. The socket members are placed between the strips 8. The section which is adapted to be connected with the house current or other supply of electricity, such as the section A in Figure 1, simply contains the two socket members, as shown in Figure 10. The terminal plugs 13 are inserted through the holes 12 at one side of the section into the sockets 10 of the two 80 socket members carried by the section A, the terminals 13 being connected by conductors with the house current or other source of supply.

The base sections B of Figure 1 are placed one on each side of the section A and each of these sections B has attached to each end thereof a post 1, the post at the outer end of each section carrying the electric lamp 5. Each base section B has a rod 15 placed between the strips of insulating material, with one end passing through the center of the socket member 9 at the inner end of the section, with said end projecting to form the plug 15', the other end of the rod terminat- 100

ing short of the other socket member and this other end is connected by a conductor 16 with one terminal of the socket for the lamp 5. The other terminal of the socket is connected by a conductor 17 with the socket member 9 at the outer end of the section. The plug 15' of each section B is placed in the socket 11 of each socket member 9 carried by the section A.

10 The base sections C are placed at right angles to the sections B and these sections C are made similar to the sections B, with the exception that the post which is not provided with a lamp is omitted. The plug forming 15' part 15' of the rod of each section C engages a part of the socket 10 of the outer socket member 9 of each section B. The two sections D do not carry posts and each of these sections D has its rod 15" extending entirely 20 through the section with its ends projecting therefrom to form the plugs. As shown in Figure 9, this rod passes through both socket members with one plug engaging a socket 11 of a socket member carried by each section C.

25 The sections E' are similar to the sections B, with the plugs of the sections D engaging portions of the sockets 10 of the members 9 of said sections B'. Then two sections D' which are similar to the sections D are placed 30 at right-angles to the sections B', with a plug of each section B' engaging a socket 10 of the member 9 at the inner end of each section B'. A gate section E, having a lamp carrying post at each end thereof, has its sockets 10 receiving 35 the plugs of the sections B', this section E having its rod 15" terminating short of both socket members, with its ends connected by the conductors 16' with the lamp sockets of the posts, the other terminals of the lamp 40 sockets being connected by the conductors 17' with the socket members 9 of the section E. The posts of the gate section are formed with the perforated ears 3' to which the gates X are pivoted.

45 From the foregoing it will be seen that the current flowing from the source will pass through one of the socket members 9 of section A through the rod 15 of one of the sections B to the lamp on the post at the outer 50 end of said section B and from the lamp, the current will pass to the socket member at the outer end of said section B, through the rod of the section C which abuts the said section B, through the lamp of the post carried by the 55 section C, then through the rod 15" of the section D to the section B' which abuts said section D, through the lamp of said section B' and through the rod thereof, then through one 60 of the sections D', then through both lamps of the section E and the rod 15" of said section E through the other section D', then through the other section B' and through the lamp of the post at the outer end of 65 said section B', then through the sections D, C and B and the lamps of the posts of said

sections C and B to the other socket member of the section A from which it returns to the source through the conductor which is connected with said other socket member.

Thus the circuit is completed through all 70 the sections and the lamps on the posts of the various sections.

As before stated, Figure 1 shows one form 75 of fence which may be formed with the sections, it, of course, being understood that other forms of fences may be constructed with the sections or by adding other sections, as desired. It will also be understood that sections may be connected together by using short lengths of conductor rods placed in the 80 sockets of the members 9 of said sections.

It is thought from the foregoing description 85 that the advantages and novel features of my invention will be readily apparent.

It is to be understood that I may make 90 changes in the construction and in the combination and arrangement of the several parts, provided that such changes fall within the scope of the appended claims.

What I claim is:—

1. A toy fence comprising posts, a sectional base to which the posts are attached, fence sections detachably connected with the posts, lamps carried by some of the posts at 95 their upper ends, socket members at the ends of the base sections, each member having a transversely arranged socket and a longitudinally arranged socket therein, plugs carried by some of the base sections for engaging the sockets of other sections and means 100 for electrically connecting the lamps on the posts with the socket members and with the plugs of the sections which carry the lamp supporting posts.

2. A toy fence comprising posts, a sectional base to which the posts are attached, fence sections detachably connected with the posts, lamps carried by some of the posts at their upper ends, socket members at the ends 105 of the base sections, each member having a transversely arranged socket and a longitudinally arranged socket therein, plugs carried by some of the base sections for engaging the sockets of other sections, means for electrically connecting the lamps on the posts 110 with the socket members and with the plugs of the sections which carry the lamp supporting posts, each base section comprising a channel-shaped member, a pair of strips of non-conducting material therein and between which the socket members are placed, the plug carrying sections having their plugs 115 also placed between the strips with portions of the plugs passing through the socket members.

3. A toy fence comprising posts, a sectional base to which the posts are attached, fence sections detachably connected with the posts, lamps carried by some of the posts at 120 their upper ends, socket members at the ends 125 of the base sections, each member having a transversely arranged socket and a longitudinally arranged socket therein, plugs carried by some of the base sections for engaging the sockets of other sections, means for electrically connecting the lamps on the posts with the socket members and with the plugs of the sections which carry the lamp supporting posts, each base section comprising a channel-shaped member, a pair of strips of non-conducting material therein and between which the socket members are placed, the plug carrying sections having their plugs also placed between the strips with portions of the plugs passing through the socket members.

of the base sections, each member having a transversely arranged socket and a longitudinally arranged socket therein, plugs carried by some of the base sections for engaging the sockets of other sections, means for electrically connecting the lamps on the posts with the socket members and with the plugs of the sections which carry the lamp supporting posts, each base section comprising a 5 channel-shaped member, a pair of strips of non-conducting material therein and between which the socket members are placed, and a rod passing between the strips in some of the base sections and through the socket members therein, the projecting ends of the rods forming the plugs of said sections.

4. A toy fence comprising posts, a sectional base to which the posts are attached, fence sections detachably connected with the 10 posts, lamps carried by some of the posts at their upper ends, socket members at the ends of the base sections, each member having a transversely arranged socket and a longitudinally arranged socket therein, plugs carried by some of the base sections for engaging the sockets of other sections, means for electrically connecting the lamps on the posts with the socket members and with the plugs of the sections which carry the lamp supporting posts, each base section comprising a 15 channel-shaped member, a pair of strips of non-conducting material therein and between which the socket members are placed, a rod passing between the strips in some of the base sections and through the socket members therein, the projecting ends of the rods forming the plugs of said sections and some of the sections having the inner ends of the rods terminating short of adjacent socket 20 members with said ends of the rods electrically connected with the lamp sockets and with the other ends of the rods projecting from the sections to form the plugs of said sections.

45 5. A toy fence comprising posts, a sectional base to which the posts are attached, fence sections detachably connected with the posts, lamps carried by some of the posts at their upper ends, socket members at the ends 25 of the base sections, each member having a transversely arranged socket and a longitudinally arranged socket therein, plugs carried by some of the base sections for engaging the sockets of other sections, means for electrically connecting the lamps on the posts with the socket members and with the plugs of the sections which carry the lamp supporting posts, each base section comprising a 30 channel-shaped member, a pair of strips of non-conducting material therein and between which the socket members are placed, a rod passing between the strips in some of the base sections and through the socket members therein to form the plugs of said sections and some of the sections having the inner ends 35

of the rods terminating short of adjacent socket members with said ends of the rods electrically connected with the lamp sockets and with the other ends of the rods projecting from the sections to form the plugs of said sections and a gate section having a 40 pair of posts thereon, each carrying a lamp with the rod therein having its ends terminating short of the socket members, with the ends of the rods electrically connected with the lamp sockets on the posts of said section.

In testimony whereof I affix my signature.

JOHN P. SCHREY.
